DESIGN FOR A RANGE OR ANALOGOUS ARTICLE

Walter C. Lindemann, Milwaukee, Wis., assignor to A. J. Lindemann & Hoverson Company, Milwaukee, Wis., a corporation of Wisconsin

Application September 13, 1938, Serial No. 79,865

Term of patent 7 years

To all whom it may concern:

Be it known that I, Walter C. Lindemann, a citizen of the United States, residing in the city of Milwaukee, county of Milwaukee, and State of Wisconsin, have invented a new, original, and ornamental Design for a Range or Analogous Article, of which the following is a specification, reference being had to the accompanying drawing, forming a part thereof.

The figure is a perspective view of a range or analogous article showing my design. The sides of the range not shown are substantially plain.

I claim:

The ornamental design for a range or analogous article, as shown and described.

WALTER C. LINDEMANN,
